APC; Nathan B. Camuti(57) **CLAIM**

The ornamental design for a kettle base, as shown and described.

DESCRIPTION

FIG. 1 is a perspective view of a kettle base, showing my new design;

FIG. 2 shows a right side view of the kettle base of FIG. 1;
FIG. 3 shows a left side view of the kettle base of FIG. 1;
FIG. 4 shows a rear view of the kettle base of FIG. 1;
FIG. 5 shows a front view of the kettle base of FIG. 1;
FIG. 6 shows a top view of the kettle base of FIG. 1; and,
FIG. 7 shows a bottom view of the kettle base of FIG. 1.
The broken lines showing portions of the kettle base are for
the purpose of illustrating environmental structure and form
no part of the claimed design.**1 Claim, 4 Drawing Sheets**FIG. 1

FIG. 2

FIG. 3

FIG. 4

FIG. 5

FIG. 7

FIG. 6
